UNITED STATES PATENT OFFICE

150,003

DESIGN FOR A PENDANT

Henry Fehrenbach, Maricopa, Ariz., assignor of one-half to C. W. Burkett, Maricopa, Ariz.

Application November 1, 1946, Serial No. 134,428

Term of patent 3½ years

(Cl. D45—15)

To all whom it may concern:

Be it known that I, Henry Fehrenbach, a citizen of the United States, residing at Maricopa in the county of Pinal, and State of Arizona, have invented a new, original, and ornamental Design for a Pendant, of which the following is a specification; reference being had to the accompanying drawing, forming a part hereof.

The dominant features of the design reside in the portions shown in full lines.

I claim:

The ornamental design for a pendant, as shown.
HENRY FEHRENBACH.
